(57) **CLAIM**

The ornamental design for a spare tire tool storage organizer, as shown and described.

DESCRIPTION

FIG. 1 is an exploded top perspective view of a spare tire tool storage organizer, showing my new design;

FIG. 2 is a bottom view thereof;

FIG. 3 is a front elevation view thereof;

FIG. 4 is a left side elevation view, the right-side elevation view being a mirror image thereof;

FIG. 5 is a bottom sectional view taken along lines 5-5 from FIG. 4 thereof;

FIG. 6 is a bottom sectional view taken along lines 6-6 from FIG. 4 thereof;

FIG. 7 is a bottom sectional view taken along lines 7-7 from FIG. 4 thereof;

FIG. 8 is a bottom sectional view taken along lines 8-8 from FIG. 4 thereof;

FIG. 9 is a bottom sectional view taken along lines 9-9 from FIG. 4 thereof;

FIG. 10 is a top plan view thereof;

FIG. 11 is a left side sectional view taken along lines 11-11 from FIG. 10 thereof;

FIG. 12 is a rear elevation sectional view taken along lines 12-12 from FIG. 10 thereof;

FIG. 13 is a top perspective view thereof; and,

FIG. 14 is a bottom perspective view thereof.
